CLAIM

The ornamental design for a candle holder, substantially as shown.

DESCRIPTION

FIG. 1 is a perspective view illustrating the front, the top, and the left side of the candle holder of my new design;

FIG. 2 is an elevation view of the front thereof;

FIG. 3 is an elevation view of the right side thereof;

FIG. 4 is an elevation view of the back thereof;

FIG. 5 is a plan view of the top thereof; and,

FIG. 6 is an enlarged fragmentary front right perspective view looking upwardly.

The bottom of the candle holder is unornamented.
